UNITED STATES PATENT OFFICE

2,424,229

METHOD OF DRYING, HEATING, AND/OR
COOLING FLOWABLE SOLIDS

John L. Erisman, Oak Park, Ill., assignor to Link-Belt Company, a corporation of Illinois

Application May 6, 1944, Serial No. 534,444

10 Claims. (Cl. 34—11)

1

This invention relates to new and useful improvements in a method of treating flowable solids, and deals more particularly with the novel steps employed for continuously drying, heating and/or cooling such solids by means of gaseous treatment fluids.

It is the primary object of this invention to provide an improved method of effecting continuous treatment of flowable solids with air, or other gaseous fluids, to remove excess moisture existing upon or within the individual material particles or lumps; to raise or lower the temperature of the material subsequent to or in preparation for some other treatment operation; to first remove the excess moisture by the application of heat and then cool the solids to a desired workable temperature, or to effect other changes in the physical characteristics of the solids.

Another important object of the invention is the provision of a method of drying, heating and/or cooling flowable solids by causing the solids to be continuously subjected to the action of gaseous treatment fluid during the entire treatment period.

A further important object of the invention is to provide a method of effecting the continuous treatment of flowable solids with air, or other gaseous fluids, by causing the solids to repeatedly move back and forth through the treatment fluid while the solids are being advanced through the treatment zone.

Still another important object of the invention is the provision of a method of subjecting flowable solids to a substantial change in temperature to accomplish drying, heating and/or cooling of the same by causing the flowable solids to repeatedly fall or cascade as a relatively shallow stream through and to be repeatedly lifted back through the flow of treatment air, or other gaseous treatment fluids.

A still further important object of the invention is to provide a method of removing heat or moisture and fines or dust particles from flowable solids by causing the solids to repeatedly fall or cascade as a relatively shallow stream through and in a direction normal to the direction of flow of gaseous treatment fluids.

A further object of the invention is to provide a method of drying, heating and/or cooling flowable solids of widely different particle or lump size or moisture content, or requiring treatment periods of vastly different duration.

Still another object of the invention is the provision of a method of drying, heating and/or

2

cooling flowable solids by causing the solids to repeatedly move back and forth through substantially parallel paths while being progressively advanced transversely of said paths from a feeding point for the untreated solids to a discharge point for the treated solids and by subjecting the solids to the action of two or more flows of air, or other gaseous treatment fluids, possessing different treatment producing characteristics or effects, which are arranged transversely of said paths.

Another object of the invention is the provision of a method of drying, heating and/or cooling flowable solids by continuously feeding the solids to a treatment zone; lifting the solids in spaced batches or masses through the zone; spilling the lifted solids to cause them to fall or cascade as a relatively shallow stream back through the zone; causing the falling or cascading solids to be advanced transversely through the zone away from the feeding location; repeating the cyclic lifting, spilling and falling or cascading treatment of the solids until the transverse advancement thereof has caused the solids to reach the discharge side of the treatment zone; discharging the solids as they are spilled after the final lifting, and circulating gaseous treatment fluid through the treatment zone so that it will flow between the batches or masses of solids being lifted and will permeate through the shallow stream of falling or cascading solids, whereby the solids will be maintained in constant heat exchange relation with the gaseous treatment fluid while moving in batches or masses or as independently falling particles or lumps, and the passage of the treatment fluid through the falling or cascading stream of solids will effect separation and removal of fines or dust particles from said stream.

40 Other objects and advantages of the invention will be apparent during the course of the following description.

In the accompanying drawings forming a part 45 of this specification and in which like numerals are employed to designate like parts throughout the same.

Figure 1 is a longitudinal sectional view of one form of apparatus which is capable of carrying out the novel method steps of effecting drying, heating and/or cooling of flowable solids embodying this invention.

Figure 2 is a longitudinal sectional view of the apparatus shown in Fig. 1 and taken at right angles to the view of this latter figure,

Figure 3 is a top plan view of the apparatus shown in Figs. 1 and 2.

Figure 4 is a fragmentary and partly broken away vertical sectional view, taken on line 4-4 of Figure 6, and is provided to illustrate the method steps in which the flowable solids are lifted through and are caused to fall or cascade through the treatment air, or other gaseous fluids.

Figure 5 is a fragmentary vertical sectional view taken on line 5-5 of Fig. 6.

Figure 6 is a fragmentary, vertical sectional view taken at right angles to the view of Fig. 4 and is provided to illustrate in a schematic manner the movements of the solids in accordance with the illustrations of Figs. 4 and 5.

Figure 7 is a diagrammatic view which is provided to depict the cyclic courses or movements of the flowable solids through the treatment zone while advancing from a feeding point to a discharging point.

Figure 8 is a vertical sectional view of a modified form of apparatus which is capable of carrying out the novel steps of this method.

Figure 9 is a vertical sectional view of the apparatus shown in Fig. 8 but taken at right angles to the view of this latter figure.

Figure 10 is a fragmentary and partly broken away vertical sectional view of the apparatus shown in Figs. 8 and 9.

Figure 11 is a similar view to Fig. 6 but illustrating the apparatus of Figs. 8 to 10 inclusive.

Figure 12 is a vertical sectional view of a further modified form of apparatus which is capable of carrying out the novel steps of this method.

Figure 13 is a vertical sectional view of the apparatus shown in Fig. 12 but taken at right angles to the view of this latter figure.

Figure 14 is a fragmentary and partly broken away vertical sectional view of the apparatus shown in Figs. 12 and 13, and

Figure 15 is a similar view to Figs. 6 and 11 but illustrates the apparatus of Figs. 12 to 14 inclusive.

In the drawings, wherein for the purpose of illustration are shown the preferred method steps embodying this invention, and first particularly referring to Figs. 1 to 7 inclusive, there is disclosed one form of apparatus which is capable of carrying out the method. This form of apparatus forms the subject matter of my copending application Serial No. 518,303, filed January 14, 1944, entitled Apparatus for drying, heating and/or cooling flowable solids. This copending application may be referred to for a more complete disclosure of the detail structural features of this apparatus.

Figs. 1, 2 and 3 disclose a housing which is referred to in its entirety by the reference character A. This housing includes any desired form of framework which is designated generally as including a top frame 20 and a bottom frame 21. This housing further includes side wall panels 22 and 23, end wall panels 24 and 25, respectively, a top wall panel 26, and a bottom wall panel 27. This housing is intended to be supported at any desired, practical, inclined angle. It will be seen as the description proceeds that the inclination of the housing will be established to properly handle the particular type of flowable solids to be treated in each given unit or apparatus. The angle to be selected, of course, will depend upon the angle of repose of the material to be treated, its moisture content, etc., and the rate at which it

is desired to cause the material to fall or cascade through the treatment zone of the housing.

For the purpose of illustrating the adjustability of the inclined angle of the housing A, side channel irons 28 are shown as being connected to the opposite sides of the bottom frame 21. The lower depending ends of these side channel irons are pivoted at 29 to a base frame 30. Adjusting channel irons or uprights 31 are adjustably connected by means of the series of apertures 32 and the bolts 33 to the upper ends of the side channel irons 28. Although not shown, the lower ends of these uprights 31 are to be pivotally connected to the base frame 30.

The entire apparatus is illustrated in Fig. 2 as being transversely canted with respect to the horizontal. This canting of the apparatus is shown as being obtained by the positioning of a block or shim 34 under one side of the base frame 30. It will be appreciated that blocks or shims of different thickness may be employed to maintain the apparatus at different canted angles with respect to the horizontal. Of course, in making a permanent commercial installation, more substantial means will be employed for rigidly and fixedly supporting the apparatus at the desired inclined and canted angles in accordance with the characteristics, etc., of the material to be treated and the method that is to be performed by the apparatus.

Referring to Fig. 1, it will be seen that the top wall panel 26 is interrupted at 35 for connection with a suitable exhaust hood 38 while the bottom wall panel 27 is interrupted at 39 for connection with the inlet box 40. The inlet opening 39 with its associated inlet box 40 and the outlet opening 35 with its exhaust hood 38 are employed for producing a flow of air, or other gaseous treatment fluid, through the treatment zone which is formed within the housing A.

Fig. 3 discloses two inlet boxes 40 and two exhaust hoods 38 as being arranged in side-by-side relation for connection with the bottom wall panel and top wall panel respectively of the housing A. For carrying out certain treatment methods, it will be satisfactory to employ one inlet box and one exhaust hood and have these elements extend the full width of the housing A. That is to say, if one gaseous treatment fluid at a uniform temperature is to be employed for effecting the desired treatment of the material passing through the housing, this air or other gaseous fluid can be handled by one inlet box and one exhaust hood. However, the use of two inlet boxes and two exhaust hoods renders the apparatus more flexible in operation. For example, the two inlet boxes and the two exhaust hoods can be employed in the same manner as one inlet box and one exhaust hood for handling a single fluid at a uniform temperature while the two boxes and the two hoods, also, can be employed for producing flows through the treatment zone of the housing A of air, or another gaseous treatment fluid, at two different temperatures to produce different treatments or to carry out different portions of the same treatment. Additionally, the two boxes and the two hoods make it possible to employ two different gaseous treatment fluids.

The inlet boxes are illustrated in Fig. 3 as being connected to inlet ducts 41 while the exhaust hoods are illustrated as being connected to exhaust ducts 42.

Fig. 2 illustrates the interior of the housing A as being provided with secondary side walls 43

and 44 which lie in parallelism with and are spaced inwardly of the side wall panels 22 and 23. These secondary side walls 43 and 44 form between them the zone in which the flowable materials are treated. These secondary side walls are spaced inwardly of the side wall panels to form transmission compartments 45 and 46. These compartments accommodate two strands of conveyor chains, sprocket wheels for the chains, etc., to maintain these transmission elements out of the direct path of the flowable solids being treated and the treatment fluid or fluids.

Figs. 1, 2 and 3 disclose a head sprocket shaft 47 as extending entirely through the upper end portion of the housing A. The outwardly projecting ends of this shaft are journaled in the pillow-blocks 48 that are mounted on exterior brackets 49. A sprocket wheel 50 is suitably fastened to one extreme outer end of the head shaft 47 and is adapted to be driven by a sprocket chain, not shown, that extends from a suitable source of power. Head sprocket wheels 51 are suitably fastened to the head shaft 47 and are located in the respective transmission compartments 45 and 46.

A foot shaft 52 is illustrated in Fig. 2 as extending entirely through the lower portion of the housing A for being journaled at its outer ends in the pillow-blocks 53 that are mounted on exteriorly positioned brackets 54. Loosely mounted on the portions of the foot shaft 52 which extend through the transmission compartments 45 and 46 are the foot wheels 55.

Two endless strands of roller conveyor chains 56 are trained over the head and foot wheels 51 and 55 and, of course, travel through the transmission compartments 45 and 46. These two chain strands, of course, are driven by the head wheels 51 keyed, or otherwise suitably secured, to the head shaft 47. As the foot wheels 55 only function to form the lower bends in the endless paths followed by the chains 56, these foot wheels need not be keyed to the foot shaft 52. By being loosely mounted on this shaft, the foot wheels 55 are permitted to seek their own positions of alignment with the head wheels 51.

The respective links or pitches of the chains 56 carry suitable attachment lugs 57 by means of which suitable conveyor flights 58 are connected to the chain strands.

Fig. 2 discloses these flights 58 as extending through the openings or slots 59 formed in the secondary side walls 43 and 44. That is to say, the flights extend a short distance at each end through these openings or slots 59. The openings or slots are continuous and correspond in elevation approximately to the endless or continuous path followed by the flights in bending around the head and foot wheels 51 and 55 respectively and in forming the lower and upper runs of the conveyor. To prevent loss of the gaseous treatment fluid, or fluids, from the treatment zone into the transmission compartments 45 and 46, the opposite ends of the flights 58 have suitably attached thereto the sealing plates 60. These sealing plates travel through endless sealing boxes 61 which lie outwardly of and follow the pattern of the openings or slots 59 formed in the secondary side walls 43 and 44. The previously described attachment lugs 57 travel through suitable slots formed in the outer side walls of the sealing boxes 61.

The flights 58 take the form of long pans or trays which extend transversely entirely through the aforementioned treatment zone provided by

the housing A. The cross sectional shape of these flight pans or trays is best illustrated in Figs. 1, 4 and 5. Each one of these flight pans or trays is formed with an inner lip 62, an intermediate bottom or base portion 63, and a back portion 64. An outer lip or flange 65 also is provided for the dual purpose of adding strength to the flight and for cooperating with the wall panels 26 and 27 for preventing by-passing of the gaseous treatment fluids admitted to the housing A through the inlet opening or openings 39. That is to say, the flights 58 cooperate with the bottom wall panel 27 to compel the inlet fluid to pass directly between the flights traveling through the lower run of the conveyor and cooperate with the top wall panel 26 to compel the treatment fluid to pass between the flights lined up with the exhaust hood or exhaust hoods 38. Figs. 4 and 5 disclose the inner lip portions 62 of the flights 58 as being of different depths. This is due to the fact that these two figures are taken on two transversely spaced, vertical sections. Figs. 2 and 4 show these inner lips 62 as being notched or cut away at 66 to accommodate the feed spout 67. The inner lip portions 62 of the flights are of greater depth laterally inwardly of this feed spout. By inspecting Figs. 4 and 5, it will be seen that the portions 62, 63 and 64 of each flight 58 form a material carrying pan or tray during the travel of the flight through the lower run of the conveyor path.

The material feed spout or chute 67 is employed for delivering the flowable solids that are to be treated into the interior of the housing at a zone which is located at the left hand side of the path of travel of the flights while they are moving through their active, lower run and adjacent the region where the flights move into the straight line path of the lower run after bending around the foot sprocket wheels 55. The feed spout or chute, therefore, extends through the side wall panel 22 and the secondary side wall 43. A trim-off plate 68 is shown in Figs. 1 and 4 as being associated with the inner delivery end of the feed spout or chute. A deflector plate 69, also, is associated with the delivery end of the feed spout or chute and functions to deflect laterally inwardly of said delivery end the solids that fall or cascade through the treatment zone in the path in longitudinal alignment with the inner end of the feed spout or chute. This cascading or falling action of the solids will be more fully explained at a later point.

Figs. 1, 2, 4 and 5 disclose a suitable shield or spill plate 70 which extends the entire distance between the secondary side plates 43 and 44 in a plane that lies just below the delivery end of the feed chute or spout 67. The function of this shield or spill plate is to prevent the material being treated from spilling down into the flights as they travel around the foot sprocket wheels.

Figs. 1 and 2 disclose a discharge spout 71 as extending into the interior of the housing A through the side wall panel 23 and the secondary side wall 44 to terminate at its upper end in close proximity to the path followed by the flights in bending around the head wheels 51. Fig. 2 shows this upper end of the discharge spout as being located adjacent the secondary side wall 44. The terminal end 72 of the discharge spout is open and is positioned to receive the fully treated solids as they are spilled from the right hand end portions of the flight pans in bending around the head sprocket wheels 51.

The manner in which the previously described

apparatus functions to carry out the novel method embodying this invention will now be described. The disclosures of Figs. 4 to 7 inclusive have been presented to facilitate this description. As no reference has been made to the disclosures of Figs. 6 and 7 in describing the apparatus, it is believed that a brief explanation of what is illustrated in these two figures will be helpful in arriving at a clear understanding.

The two side walls shown in Figs. 6 and 7 are the secondary side walls 43 and 44 that were specifically referred to in connection with the disclosure of Fig. 2. The feed chute or spout 67 is illustrated as being located in the lower left hand portion of each one of these two disclosures. The discharge chute 71 is illustrated as being associated with the upper right hand corner of the illustrated apparatus and as having its open upper end or terminal 72 arranged to receive material that has been completely treated.

The cut-off plate 68 and the deflector plate 69 are additionally illustrated in connection with the feed chute or spout 67. In referring to the disclosures of Figs. 4 and 5, reference was made to the shield or spill plate 70 in connection with the feed chute or spout 67. This shield or spill plate 70 is shown in each of Figs. 6 and 7. The disclosures of these last two mentioned figures, therefore, are limited to the treatment zone of the apparatus, or the zone or area in which the novel steps of the method are carried out.

The sectional view of Fig. 4 shows the flights 58 while traveling through their lower, active run and while bending partly around the head sprocket wheels 51 and the foot sprocket wheels 55. The flights 58 are employed during this portion of their total travel for receiving the flowable solids to be treated from the feed chute or spout 67, conveying the solids upwardly through the path of flow of the gaseous treatment fluid that is delivered to the treatment zone of the apparatus through the inlet box 40 and the inlet opening 39. This gaseous treatment fluid flows between the spaced flights traveling past the inlet opening 39. The direction of movement of the treatment fluid is indicated by the arrow line 73. This treatment fluid naturally moves in heat exchange relation with the entire exposed under surface of each one of the flights 58, the exposed upper surface of each flight, and the exposed upper surface of each charge or batch of solids being carried by the flight trays or pans. Therefore, this flow of the gaseous treatment fluid between the flights and their charges or batches of solids will help to dry, heat and/or cool the conveyed solids.

It will be recalled that the housing A is intended to be supported in such a manner that the lower active run of the conveyor is inclined at a desired angle with respect to the perpendicular. Additionally, the housing A is intended to be transversely canted at any desired angular relation with respect to the horizontal. The inclination of the active run of the conveyor, which is traveling in the direction of the arrow line 74 in each of Figs. 4 and 5, is clearly illustrated in these two figures while the transverse canting is shown by the disclosures of Figs. 6 and 7.

Figs. 4, 6 and 7 show the feeding of the solids into the left hand end portion of each one of the conveyor pans as they move past the delivery end of the feed spout or chute 67. This amount of untreated solids that is fed to the left hand end portion of each flight pan as it passes the feed spout or chute may be theoretically considered as forming a part of a band of solids that is lifted

by the flights through the flow of gaseous treatment fluid and along the secondary side wall 43. This initial upward travel of the untreated solids is represented by the solid arrow line 75 in Fig. 7.

As the flights 58 start bending around the head sprocket wheels 51, the pans of the flights start spilling the conveyed solids over the outer edges of their inner lips 62. This spillage is depicted in Figs. 4 and 6 and is indicated by the reference character 76. As the material is spilled from the pans of the various flights, it is caused to fall or cascade downwardly over the upwardly traveling flights 58 and their charges or batches of solids. This cascading or downward falling of the solids is represented by the relatively shallow stream 77 shown in Figs. 4 and 5. The dotted lines 77 of Fig. 6 also represent this falling or cascading stream of solids. The falling or cascading of the initial band of material is represented in Fig. 7 by the dash arrow line 78. To prevent the portion of the solids which is falling or cascading downwardly along the secondary side wall 43 from interfering with the initial feeding of solids to the left hand end portions of the flight pans, the deflector plate 69 is provided and functions to direct this material laterally to the side of the feed spout or chute 67.

The falling or cascading material is finally stopped by the shield or spill plate 70 and is again fed to the flight pans as they advance beneath the bottom edge of this plate 70. The remaining solid arrow lines 79 of Fig. 7 are intended to represent this repeated upward movement of the solids in the form of charges or batches carried by the conveyor pans. Of course, each time the solids arrive at the region where the flights bend around the head sprocket wheels 51, the solids are again spilled over the inner edges of the flight lips 62. This repeated falling or cascading of the solids is represented by the remaining dash lines 80 of Fig. 7.

Due to the canted position of the housing A, the falling or cascading solids will be caused to advance transversely of the treatment zone. This transverse advancement will occur each time the solids are caused to fall or cascade through the treatment zone with the result that the solids will progress in a step-by-step manner toward the right, as viewed in Figs. 6 and 7. It will be appreciated, of course, that the material does not move upwardly and downwardly in definite or distinguishable bands as indicated by the showing of Fig. 7. Fig. 6 shows the flights 58 filled with material throughout their lengths. There naturally will occur some lateral flow or mixing of the solids as they are charged into the trays or pans of the flight by the shield or spill plate 70. This lateral or transverse intermixing, also, will occur while the solids are falling or cascading downwardly over the advancing flights.

When the solids are finally lifted through a path or band that lies adjacent the secondary side wall 44 and are spilled from the right hand ends of the flight pans as the flights bend around the head sprocket wheels 51, the open upper end of the discharge chute 71 will receive the spilled solids and conduct them out of the housing A. This discharge is represented by the character 81 in each of Figs. 6 and 7.

It was pointed out above that the air, or other gaseous treatment fluid, delivered to the treatment chamber of the housing A through the inlet opening 39 passes between the flights 58 and their charges of the solids. After passing between the flights, the treatment fluid permeates

through the relatively shallow stream of solids 11 cascading downwardly over the advancing flights. This places the treatment fluid in intimate contact with each particle or lump of solids in the stream 11. Consequently, each particle or lump of the solids is directly subjected to the treatment action of the air, or other gaseous fluids. Once the material to be treated is introduced to the treatment zone of the housing A, it will remain at least in heat exchange relation with the treatment fluid until it is discharged from the housing by the chute 11. This will be apparent when it is considered that the treatment fluid passes between the charges or batches of solids while they are being elevated and passes between the individual particles or lumps of solids as they are cascading over the advancing flights. Additionally, the atmosphere within the treatment chamber above the shield or spill plate 10 and between the two straight runs of the conveyor flights will assume the temperature characteristics of the treatment fluid that is circulated through the treatment zone from the inlet box 40 to the exhaust hood 38.

Let us now consider the manner in which the described apparatus carries out the method of drying flowable solids. If the apparatus is provided with a single inlet box 40, the treatment air, or other gaseous fluid, delivered to the treatment zone of the housing A will be of uniform temperature throughout the entire cross section of the inlet box. This treatment fluid, as has been described above, will flow between the advancing flights 58 in heat exchange relation with the charges of solids carried by these flights and will permeate through the cascading stream of solids 11. As the solids progressively advance transversely of their two, substantially parallel, paths of movement, the excess moisture existing upon or within the individual particles or lumps will be removed. As the individual particles or solids give up their moisture, the material will become less sticky or tacky and will fall or cascade as a looser, less compact stream. Consequently, the flowing treatment fluid, in passing through the cascading stream, will be permitted to separate and remove more and more fines or dust particles from the solids as the latter advance across the treatment zone and will complete this separation and removal of the fines or dust particles by the time the solids reach their point of discharge from the housing A.

If two inlet boxes 40 and exhaust hoods 38 are employed, treatment fluid of the same character or temperature can be employed or treatment fluids of different characters or temperatures can be circulated through the aligned sets of inlet boxes and exhaust hoods. For example, if the drying method is to be performed, air at different temperatures can be circulated through the parallel sets of inlet boxes and exhaust hoods with the air of higher temperature being circulated through the portion of the treatment zone located on the feeding side while the air of lower temperature will be circulated through the discharge side of the treatment zone.

No attempt has been made to disclose the use of a partition for dividing the treatment zone of the housing into two distinct chambers but it is obvious that such a partition can be employed.

If the method of both drying and cooling the flowable solids is to be carried out by this apparatus, air or other gaseous fluid of the proper high temperature will be circulated through the aligned inlet box and exhaust hood located on

the feed side of the housing while air, or other gaseous fluid of considerably lower temperature will be circulated through the discharge side of the treatment zone by the remaining inlet box and exhaust hood. A dividing partition for the treatment zone will be more essential in carrying out this combined drying and cooling method.

When the apparatus is employed for carrying out the method of cooling flowable solids, either one or two inlet boxes and one or two exhaust hoods can be employed. If one inlet box and exhaust hood are employed, air, or the like, of uniform temperature is circulated through the entire width of the treatment zone. If two inlet boxes and two exhaust hoods are employed, air of the same low temperature can be circulated through the entire width of the treatment zone or air at different temperatures can be circulated through the two half portions of the treatment zone.

Figs. 8 to 11 inclusive disclose a modified form of apparatus which is capable of carrying out the same drying, heating and/or cooling method steps as have been described in connection with the apparatus of Figs. 1 to 7 inclusive. The primary differences between the two structures reside in the conveying mechanism, the means employed for delivering the charges or batches of the solids to the conveyor flights, the means for supporting the falling or cascading stream of solids, and the means employed for progressively advancing the solids transversely of the treatment zone. For that reason, the housing, its supporting means, and the inlet boxes and exhaust hoods will be referred to only in a general way while the remaining mechanism will be rather specifically described.

The housing A' may be fabricated in any desired manner to provide the necessary strength and airtight characteristics. The housing is supported for pivotal movement, as at 82 to enable the housing to be at any desired inclined angle with respect to the vertical. This housing need not be canted relative to the horizontal because positive means are employed for progressively advancing the solids transversely of the treatment zone.

One or more inlet boxes 83 are employed for delivering the air, or other gaseous treatment fluid, to the interior of the housing A' while one or more exhaust hoods 84 are employed for carrying off the fluid after it has passed through the treatment zone.

A head shaft 85 passes through the upper portion of the housing A' and is supported in suitable outboard pillow blocks 86. A driving sprocket wheel 87 is suitably attached to one projecting end of this head shaft. Head sprocket wheels 88 are mounted on the head shaft and function to train the two strands of conveyor chain 89 around the head bend of the conveyor path.

A foot shaft 90 passes through the lower portion of the housing A' and is journaled at its opposite ends in suitable outboard pillow blocks 91. Keyed, or otherwise suitably secured, to the foot shaft are the foot sprocket wheels 92. These foot wheels train the two conveyor chain strands 89 around the foot bend of the conveyor path.

A suitable number of conveyor flights 93 are attached to the links or flights of the conveyor chains 89 at their opposite ends. These flights 93 take the form of buckets which are arranged to convey material while moving through the lower, active run of the conveyor path. The di-

11

rection of movement of the conveyor buckets is represented by the arrow line 94 in Fig. 10.

A suitable feed chute 95 is employed for delivering the solids to be treated into the housing A'. Figs. 9 and 11 show this feed chute 95 as delivering the untreated solids to the left hand lower corner portion of the treatment zone. A suitable deflector plate 96 overlies the inner delivery end of the feed chute for deflecting laterally the first or initial course of solids cascading through the treatment zone.

The flowable solids delivered by the feed chute 95 are received in the measuring compartments 97 of a conventional star feeder 98. This star feeder extends entirely across the treatment chamber of the housing A' and is provided with an entrance opening 99 for passing not only the solids that are delivered by the feed chute 95 but also the solids that are cascaded through the treatment zone throughout the width of the said zone. This star feeder has a delivery spout 100 that functions to charge into the advancing flight buckets 93 measured charges of the flowable solids being treated. This spout 100 also extends the full width of the treatment zone and it delivers the solids to the full width of each conveyor bucket 93. The shaft 101 of the star feeder is illustrated as extending outwardly of one side of the housing A' for having a sprocket wheel 102 suitably fastened thereto. A sprocket chain 103 is trained over the sprocket wheel 102 and over a driver sprocket 104 which is suitably fastened to the foot shaft 90 of the conveyor. The star feeder, therefore, is driven from this foot shaft.

The conveyor buckets 93 elevate the successive charges or batches of solids through the treatment zone of the housing and past the inlet opening of the inlet box 83. This box functions to deliver the air, or other gaseous treatment fluid in the direction of the arrows 105 through the spaces left between the conveyor buckets 93 and in heat exchange relation with the exposed under surfaces of these buckets and the exposed top surfaces of the charges or batches of solids carried thereby. As the conveyor buckets bend around the head sprocket wheels 88, the buckets spill their charges or batches of solids over the inner lips of the buckets. This spilling material is represented by the character 106 in Figs. 10 and 11.

Instead of permitting the downwardly flowing solids to cascade over the upwardly advancing conveyor buckets 93, spaced louvres 107 are provided for defining the course of the relatively shallow stream of solids which is represented by the character 108 in Figs. 10 and 11. Due to the spacing of these louvres, the air, or other treatment fluid, is permitted to pass therebetween, as indicated by the arrow lines 109, and to permeate through the stream 108. This treatment fluid, therefore, is placed in direct contact with the individual particles or lumps of the solids in the shallow stream.

A paddle, or spirally pitched blade, conveyor 110 is positioned within the treatment chamber and is arranged so that the paddles or blades 111 dip into the cascading stream of solids 108. These blades 111 are illustrated in Fig. 11 as functioning to progressively advance the cascading solids transversely of the treatment zone. This paddle conveyor, therefore, performs the same function as the canting of the apparatus of Figs. 1 to 7 inclusive.

Fig. 9 shows the shaft 112 of this paddle conveyor as extending outwardly of the housing A'

12

for being driven by the conveyor head shaft 85 by means of the sprocket chain 113 and the sprocket wheels 114 and 115.

As this apparatus of Figs. 8 to 11 inclusive functions in the same manner as the apparatus of Figs. 1 to 7 inclusive for carrying out the method steps of drying, heating and/or cooling flowable solids, it is not believed to be necessary to repeat this description. As the fully treated solids are spilled from the right hand end portions of the conveyor buckets 93, in bending around the head sprocket wheels 88, the solids are received by the open up end 116 of the discharge chute 117 and are carried by this chute out of the housing A'.

Figs. 12 to 15 inclusive disclose another form of apparatus which is capable of performing the various steps of the previously described method of drying, heating and/or cooling flowable solids. This apparatus includes a housing A'' which is supported for pivotal movement at 118 to enable it to be positioned at different inclined angles with respect to the vertical. It is not necessary to support the housing A'' canted with respect to the horizontal because other means are employed for progressively advancing the solids transversely of the treatment zone provided by the housing.

One or more inlet boxes 119 are provided for delivering air, or other gaseous treatment fluid, to the treatment zone within the housing. One or more cooperating exhaust hoods 120 are connected to the housing A'' to carry off the gaseous fluids after the solids have been treated therewith.

A head shaft 121 extends through the upper portion of the housing and is mounted in suitable bearings 122 at its opposite ends. One end of this shaft has suitably secured thereto a sprocket wheel 123 that is to be driven by any suitable source of power. Head sprocket wheels 124 are suitably fastened to the head shaft 121.

A foot shaft 125 is shown as extending through the lower portion of the housing A''. The opposite end portions of this shaft are journaled in the bearings 126. Foot sprocket wheels 127 are supported on the foot shaft 125.

Two strands of conveyor chains 128 are trained over the head and foot sprockets 124 and 127. Angle bars 129 are suitably connected at their opposite ends to the links or pitches of the conveyor chains 128. Suitably attached to these supporting angle bars 129 is an endless woven wire mesh belt 130. Flight mounting angles 131 are suitably attached to the supporting angle bars 129. These angles 131 are positioned on the inner side of the wire belt 130. Flight plates 132 are attached to the angles 131. It will be noted that the angles 131 and the flight blades 132 overlap for a portion of their depth. This overlap is to permit the blades 132 to be adjusted with respect to their mounting angles 131.

A feed chute 133 is employed for delivering the untreated flowable solids to the lower left hand corner of the treatment zone provided in the housing A''. This untreated material is to be picked up in charges or batches by the flights 132 and the wire mesh belt 130 for being elevated through the path of the treatment fluid that is delivered to the treatment zone by the inlet box or boxes 119. This treatment fluid flows in the direction of the arrow lines 134 and will pass in heat exchange relation with the charges or batches of solids being elevated by the conveyor. The treatment fluid, of course, will pass through

the uncovered portions of the wire mesh belt 130. A shield or spill plate 135 extends transversely of the treatment chamber immediately below the delivery end of the feed chute 133. This shield or spill plate, therefore, cooperates in delivering the untreated solids to the flights and performs the additional function of returning the spilled or cascaded solids to these flights as they pass upwardly beneath the lower edge of the shield or plate.

As the flights 132 bend around the head wheels 124, the conveyed solids are spilled over the inner edges of the flights. This spilling is designated by the reference character 136 in Figs. 14 and 15.

The spilled solids are caused to cascade as a relatively shallow stream 137, see Figs. 14 and 15, downwardly over the flights 132 and the charges or batches of flowable solids being elevated by these flights. Consequently, the treatment fluid that passes between the flights and their batches of solids is caused to permeate through the shallow stream in direct contact with the individual particles or lumps of the cascading solids.

To accomplish progressive, transverse advancement of the solids each time they cascade through the treatment zone, deflector strips 138 are provided. Figs. 13 and 15 illustrate these deflector strips as being canted, or arranged on the bias, with respect to the length of the housing A''. These strips, therefore, will guide or deflect the solids progressively across the treatment zone. Transverse baffles 139 are illustrated in Figs. 12 to 14 inclusive and cooperate with the shield or spill plate 135 in confining the air, or other gaseous treatment fluid, to a straight through flow with respect to the treatment zone. That is to say, the plates 135 and 139 located adjacent the foot and head wheels 127 and 124 respectively prevent the treatment fluid from flowing into the opposite end portions of the housing A'' while the intermediate baffle plate 139 prevents the treatment fluid from partaking of upward movement from the lower portion of the treatment zone into the upper portion of this zone.

It will be obvious to persons skilled in the art that this apparatus of Figs. 12 to 15 inclusive will function in the same manner as the previously described apparatus of Figs. 1 to 7 inclusive, etc., and for that reason it will not be necessary to repeat a description of the method steps in connection with this third form of apparatus.

It is to be understood that various changes in practicing the herein described method, and in the shape, size, and arrangement of parts of the apparatus that are shown as being capable of carrying out the method, as come within the scope of the subjoined claims, may be resorted to without departing from the spirit of the invention.

Having thus described the invention, I claim:

1. A method of treating flowable solids, comprising feeding the solids to be treated to a treatment zone, repeatedly lifting all of the solids in spaced batches through a straight inclined path in the treatment zone, repeatedly spilling solids that have been moved as batches as a relatively shallow stream through the treatment zone in the opposite direction to and in cascading contact with substantially all of the spaced batches of solids, transferring solids from the batches to the stream and from the stream to the batches at spaced points in the treatment zone, flowing gaseous fluid through the treatment zone substantially at right angles to the directions of move-

ment of the batches and the stream of solids to cause the fluid to pass between the moving batches of solids and to permeate through the stream of solids, and discharging the treated solids from the treatment zone.

2. A method of treating flowable solids, comprising producing a gaseous treatment fluid flow of large cross-sectional area through a treatment zone, continuously moving closely spaced batches

10 of the solids through a straight inclined path at right angles to the axis of the flow of treatment fluid so that the large cross-sectional area of the flow will simultaneously effect heat exchange between the fluid and several batches of solids as 15 all of the fluid flows through the spaces between batches, continuously moving solids that have been moved as batches back through the flow of treatment fluid as a single relatively shallow, transversely and longitudinally continuous stream 20 that parallels the path of movement of said batches and lies down stream thereof with reference to the direction of movement of the fluid to effect further heat exchange between the solids in the stream and the fluid, progressively advancing the solids transversely of the stream, continuously feeding untreated solids to one side of the treatment zone, and continuously discharging treated solids from the other side of said treatment zone.

3. A method of treating flowable solids, comprising continuously advancing batches of the solids upwardly along an inclined path with the batches being so closely positioned that the inclination of their path of travel will cause the batches to be arranged in stepped relation with each batch only partially projecting from beneath the next preceding batch and that only relatively narrow flow paths for gaseous treatment fluid will be left between the batches, spilling all of the batches of solids at the upper end of their inclined path of travel so that spilled solids will flow as a relatively shallow stream downwardly over substantially all of the stepped arrangement of advancing batches of solids and past the ends of

45 said relatively narrow treatment fluid flow paths that are left between the advancing batches, stopping the downward travel of the solids in the stream at the lower end of said inclined path, gathering the stopped material in batches, again 50 advancing the material gathered in batches along the said inclined path so as to repeat the movement of the solids in batches and in the stream, producing a flow of gaseous treatment fluid substantially at right angles to the directions of movement of the solids in batches and in the stream and through substantially the entire length and breadth of the area in which the stream of solids flows over the advancing batches of solids so that the fluid will pass through the 55 said flow paths and will permeate through the stream of solids, continuously feeding untreated solids to one side of the lower end of said inclined path to be gathered into the batches that are advanced along said path, and continuously discharging treated solids from the other side of said inclined path.

4. A method of treating flowable solids, comprising advancing relatively long and shallow batches of the solids upwardly along an inclined path with the batches being so closely positioned that the inclination of their path of travel will cause the batches to be arranged in stepped relation with each batch only partially projecting from beneath the next preceding batch and that 70 only relatively narrow flow paths for gaseous

treatment fluid will be left between the batches, spilling all of the batches of solids at the upper end of their inclined path of travel so that spilled solids will flow as a single relatively shallow, transversely and longitudinally continuous stream downwardly over all of the stepped arrangement of advancing batches of solids and past the ends of said substantially relatively narrow treatment fluid flow paths that are left between the advancing batches so as to bridge said paths, stopping the downward travel of the solids in the stream at the lower end of said inclined path, gathering the stopped material in batches, again advancing the material gathered in batches along the said inclined path so as to repeat the movement of the solids in batches and in the stream, producing a flow of gaseous treatment fluid substantially at right angles to the directions of movement of the solids in batches and in the stream and through substantially the entire length and breadth of the area in which the stream of solids flows over the advancing batches of solids so that the fluid will pass through the said fluid flow paths and will be compelled to permeate through the stream of solids bridging said path ends, continuously feeding untreated solids to one side of the lower end of said inclined path to be gathered into the batches that are advancing along said path, and continuously discharging treated solids from the other side of said inclined path.

5. A method of treating flowable solids, comprising continuously advancing batches of the solids upwardly along an inclined path with the batches being closely positioned so as to leave only relatively narrow flow paths for gaseous treatment fluid between the batches, spilling all of the batches of solids as they arrive at the upper end of their inclined path of travel and cascading spilled solids as a single relatively shallow, transversely and longitudinally continuous stream downwardly along an inclined path that parallels and overlies the path of travel of the batches of solids, stopping the downward travel of the solids in the stream, gathering the stopped material in batches, again advancing the material gathered in batches along the first mentioned inclined path so as to repeat the movement of the solids in batches and in the stream, producing a flow of gaseous treatment fluid substantially at right angles to the inclined paths of the batches and the stream and through substantially the entire length and breadth of the area covered by the advancing batches of solids and the cascading stream of solids so that the fluid will pass through the fluid flow paths between the batches and will permeate through the stream of solids, continuously feeding untreated solids to one side of the inclined path for the batches to be gathered into the batches that are advancing along said path, progressively advancing the solids transversely of the shallow stream, and continuously discharging treated solids at the opposite side of the inclined path for the batches.

6. A method of treating flowable solids, comprising feeding the solids to be treated to a treatment zone, repeatedly lifting the solids in spaced batches through an inclined path in the treatment zone, spilling the solids each time they arrive at the upper end of said inclined path to cause spilled solids to fall and in falling to cascade as a relatively shallow stream over substantially all of the spaced batches of solids being lifted through the inclined path, transferring

cascaded solids from the lower end of the shallow stream to the lower end of said inclined path, again gathering the transferred solids into batches, flowing gaseous fluid through the treatment zone in a manner which will cause the fluid to pass between the batches of solids being lifted and between the individual particles or lumps of solids as they cascade from one to the other of said batches of solids, and discharging the treated solids from the treatment zone.

7. A method of treating flowable solids, comprising feeding the solids to be treated to a treatment zone at a point adjacent one margin thereof, repeatedly lifting the solids in spaced batches through an inclined path in the treatment zone, spilling the solids each time they arrive at the upper end of said inclined path to cause the solids to fall and in falling to cascade as a relatively shallow stream over substantially all of the spaced batches of solids being lifted through the inclined path, transferring the cascaded solids from the lower end of the shallow stream to the lower end of said inclined path, again gathering the transferred solids into batches, progressively advancing the solids away from the feeding point and toward the opposite margin of the treatment zone each time the solids are caused to fall or cascade through the treatment zone, flowing gaseous treatment fluid through the treatment zone in a manner which will cause the fluid to pass between the batches of solids being lifted and between the individual particles or lumps of solids as they cascade from one to the other of said batches of solids, and discharging the treated solids from the treatment zone when the solids reach said opposite margin of the treatment zone.

8. A method of treating flowable solids, comprising producing a flow of gaseous treatment fluid of a desired uniform temperature through a treatment zone, continuously moving spaced batches of the solids upwardly through an inclined path that passes through the flow of treatment fluid at an angle to the axis of said flow to effect heat exchange between the batches of solids and the fluid as the fluid passes between the batches, continuously spilling the solids as they reach the upper end of said inclined path to cascade spilled solids downwardly over substantially all of the batches of solids moving upwardly through the inclined path as a relatively shallow stream to effect repeated direct heat exchange between the individual particles or lumps of the solids as they fall past the spaces between batches and through the treatment fluid that has passed between said batches, transferring cascaded solids from the shallow stream at the lower margin of the treatment zone to the lower end of said inclined path for being gathered into batches so as to effect repeated movement of the solids through the treatment fluid in batches and in a stream, progressively advancing the solids transversely of the inclined path, continuously feeding untreated solids to one side of the inclined path for gathering into batches, and continuously discharging treated solids from the other side of said path.

9. A method of treating flowable solids, comprising producing parallel flows of gaseous fluid possessing different treatment producing effects through a treatment zone, continuously feeding the solids to be treated to one margin of the treatment zone, repeatedly lifting the solids in spaced batches through an inclined path in the treatment zone that lies substantially at right angles to the direction of movement of the flows

of treatment fluid in said zone so that the fluid will pass between said batches of solids being lifted, spilling the solids each time they arrive at the upper end of said inclined path to cause all of the solids to fall and in falling to cascade as a relatively shallow stream over all of the spaced batches of solids being lifted through the inclined path, transferring all of the cascaded solids from the lower end of the shallow stream to the lower end of said inclined path, again gathering the transferred solids into batches, progressively advancing the solids from the feeding location transversely of the parallel flows of treatment fluid toward the opposite margin of the treatment zone, and continuously discharging the treated solids as they arrive at said opposite margin.

10. A method of treating flowable solids, comprising producing a gaseous treatment fluid flow of large cross sectional area through a treatment zone, continuously moving spaced batches of the solids to be treated upwardly along an inclined path which is arranged substantially at right angles to the axis of and which passes through the flow of treatment fluid; after the batches of solids have passed through the fluid flow and have reached a location above the same, spilling the batches of solids so that they will fall on to advancing batches also located above the fluid flow and will be assembled into a relatively shallow stream that will cascade downwardly over substantially all of the batches of solids moving upwardly through the fluid flow; after the cascading solids have passed through the fluid flow and have reached a location below the same, re-

gathering the cascaded solids into batches for repeated movement upwardly along said inclined path and through the fluid flow; continuously feeding untreated solids to one side of the treatment zone at the location where cascaded solids are being gathered into batches; progressively advancing the solids away from the feeding location and transversely of the fluid flow, and continuously withdrawing treated solids from the opposite side of the treatment zone.
